UNITED STATES PATENT OFFICE.

WILLIAM C. HAPPE, OF DAVENPORT, IOWA.

RAILROAD-TRUCK.

SPECIFICATION forming part of Letters Patent No. 715,791, dated December 16, 1902.

Application filed July 14, 1902. Serial No. 115,679. (No model.)

To all whom it may concern:

Be it known that I, WILLIAM C. HAPPE, a citizen of the United States, residing at Davenport, in the county of Scott, State of Iowa, have invented certain new and useful Improvements in Railroad-Trucks; and I do hereby declare the following to be a full, clear, and exact description of the invention, such as will enable others skilled in the art to which it appertains to make and use the same.

This invention relates to railways; and it has for its object to provide a railway in which the rails will be elevated and upon which the cars will be held securely against displacement when traveling at enormous speed.

A further object of the invention is to provide a construction which will permit of use of lighter cars than is customary.

An additional object of the invention is to provide an arrangement for holding the cars upon the track which is adjustable and may be adjusted at both sides of the cars from a single point upon the car, other objects and advantages of the invention being understood from the following description.

In the drawings forming a portion of this specification, and in which like numerals of reference indicate similar parts in the several views, Figure 1 is a transverse section through a trackway embodying the present invention and a car thereon, portions being shown in elevation. Fig. 2 is a side elevation of a portion of a trailer-car and illustrating the arrangement of the wheels at one side of the truck. Fig. 3 is a view similar to Fig. 2 and showing a double truck such as is used upon the motor-car. Fig. 4 is an end elevation of a truck. Fig. 5 is a section on line 5-5 of Fig. 2 and showing the sliding arrangement of the upper wheel at one side of the truck. Fig. 6 is an elevation of the screw at one end of the truck which adjusts the upper wheel. Fig. 7 is a plan view of the mechanism for adjusting all of the screws of the truck simultaneously. Fig. 8 is an elevation of one of the tension-screws. Fig. 9 is an end elevation of a motor-car and illustrating the truck and the arrangement of the parts for varying the tensions of the springs that hold the upper wheels against the angular rails.

Referring now to the drawings, the present trackway comprises a plurality of pairs of up-

wardly-converging posts 10 and 11, which are preferably of skeleton formation, as shown, the lower ends of which are secured to and 55 rest upon the foundations or bases 12 and 13 and are connected at their lower ends by the strut 14, there being also ties 15 and 16, which extend diagonally from the lower ends of the posts to the upper portions of the opposite 60 posts. Secured to the posts of each pair is a cross-beam 17, on which are mounted a pair of beams 18 and 19, which support rails 20 and 21, the beams 18 and 19 being connected by a suitable number of ties 22. Upon the 65 upper ends of the posts and extending longitudinally of the trackway are the angle-irons 23, upon which are secured the channel-irons 24, one flange 25, which is the inner flange of each channel-iron, receiving be- 70 tween it and the flange 26 of the corresponding angle-iron one flange of an angle-iron 27, the several flanges being riveted together, as shown. The angle-irons 23 are in fact upper rails and are engaged on their under faces 75 by the upper wheels of the car-trucks hereinafter described. The trucks of the cars that travel upon this trackway have lower supporting-wheels 30, that run upon the rails 20 and 21, and have also upper wheels 50, that 80 run against the under faces of the upper rails and prevent the wheels 30 from leaving the lower rails. The passenger-cars have their trucks provided with one upper wheel at each side, as shown in Fig. 2, while the motor-car 85 has two upper wheels at each side of the truck, as shown in Fig. 3.

In Fig. 2 of the drawings there is shown the truck for passenger-cars, while in Fig. 3 there is shown a truck for a motor-car, Figs. 4 and 90 6 having also reference to the motor-car, as well as Figs. 7 and 8. The bolster 30' of the truck is disposed upon the longitudinal beams 31', having boxes 32, in which turn the ends of the axle 33, that carries the wheels 30, that 95 run on the rails 20 and 21. Upon the upper face of the bolster 30' is mounted the U-shaped frame 35, the ends 36 and 37 of which are passed upwardly at the sides of the body of the car 38 and are slidably engaged with 100 die-plates 39, which latter are secured to the sides of the car-body. The truck is thus held against movement longitudinally of the car-body and the car-body is permitted to have

vertical movement with respect to the truck-bolster, the body being sustained by the helical springs 40, which rest with their lower ends upon the frame 35, while upon their upper ends rest the longitudinal sills 41 of the car-body.

Upon the sides of the car-body at opposite sides of each of the plates 39 are secured die-plates 42 and 43, in which are slidably mounted plates 44 and 45, having other plates 46 and 47 slidably mounted therein for vertical movement, and these last-named plates have openings therethrough, through which are passed the axles 49 of wheels 50. The axles 49 are mounted in bearings 51 on body-bolsters 52. Passed through the body-bolsters 52 and through the corners of the truck-frames 53 are bolts 54, the lower portions of which directly above the truck-frame are threaded, and with the threaded portions are engaged nuts 55, having gear-teeth on their outer faces, so that they are in effect pinions. On the bolts 54 and resting with their ends, respectively, against the bolsters 52 and the pinions 55 are helical springs 56, which sustain the bolsters 52 and therewith the axle 49 and its wheels 50.

Mounted upon the truck are the shafts 57 and 58, each having a pair of worms 59, and each of these worms engages a pinion 55. The shafts 57 and 58 carry bevel-gears 60 and 61, which mesh with similar gears 62 and 63 on a transverse shaft 64, having also a pinion 65. A vertical shaft 66 is mounted on the front platform of the car, and fixed to its upper end is a hand-wheel 67, which is located convenient to the motorman. The shaft 66 carries a worm 68, which meshes with the pinion 65, and thus when the hand-wheel is rotated the shafts 57 and 58 will be actuated to turn the pinions 55 in corresponding direction, so that they will be fed upwardly or downwardly of the bolts. As the pinions feed upwardly the tensions of the springs 56 are increased and the wheels 50 are pressed upwardly with increased force. The wheels 50 are arranged to run against the lower sides of the angular upper track-rails and prevent the truck from rising a distance sufficient to cause the wheels to leave the track-rails 20 and 21.

In Figs. 2 and 5 is shown the arrangement of truck for passenger-cars, wherein there is only one upper wheel at each side of the truck. The passenger-car is also shown in Fig. 1 of the drawings. Referring now to Fig. 2, the car-body 70 has a die-plate 71 fixed thereto, in which is slidably engaged an arm 72 of a U-shaped plate similar to the plate or frame 35, it being understood that there is a die-plate 71 at each side of the passenger-car, the U-shaped plate or frame being mounted directly upon the truck-bolster 73 and there being helical spring 40 between the web of the U-shaped frame and the sills on the bottom of the car-body to sustain the car-body yieldably. In the end portions 72

of the U-shaped frame are slidably mounted plates 74, having stub-shafts 75, which carry wheels 76, which run against the under side 70 of the angular upper rails of the trackway. Helical springs 77 are disposed upon the bolster 73 and sustain the plates 74 yieldably. With this construction it will be seen that the upper wheels prevent the lower wheels 75 from rising from the track on which they run, the play of the plates 74 vertically being less than the depths of the flanges of the lower wheels, so that the lower wheels cannot rise sufficiently far to permit their flanges to pass 8c over the rails.

What is claimed is—

1. A railway-car comprising a truck including a frame having supporting-wheels and a bolster, a U-shaped frame mounted upon the bolster, a car-body mounted in the U-shaped frame, additional wheels in parallel planes with the corresponding first-named wheels and yieldable means sustained by the truck for holding the last-named wheels in spaced 90 relation to the first-named wheels.

2. The combination with a truck-frame provided with wheels of a bolster upon the frame, a U-shaped frame upon the bolster, a car-body mounted in the U-shaped frame for 95 vertical movement and sustaining-springs for the body between the body and the web of the U-shaped frame.

3. A truck for cars comprising a frame having supporting-wheels a U-shaped frame sustained by the first-named frame and adapted to receive therein a car-body, and upper wheels in parallel planes with the corresponding supporting-wheels, said upper wheels being connected slidably to the sides of the U- 100 shaped frame and having yieldable sustaining means supported from the truck-frame.

4. A railway-car comprising a truck including a frame having supporting-wheels and a bolster, a U-shaped frame mounted upon the bolster, a car-body mounted in the U-shaped frame, additional wheels in parallel planes with the corresponding first-named wheels, yieldable means sustained by the truck for holding the last-named wheels in spaced 105 relation to the first-named wheels, and means for simultaneously adjusting the tensions of all of the yieldable supporting means.

5. A car comprising a truck including a frame having a bolster mounted thereon, a 110 U-shaped frame mounted upon the bolster, a body disposed slidably in the U-shaped frame, plates slidably mounted upon the sides of the body, lower wheels mounted in the truck-frame, upper wheels mounted in 115 said sliding plates, bearing-boxes for the axles of the upper wheels in which the axles are engaged, bolsters upon which the boxes are mounted and sustaining-springs for said bolsters mounted upon the truck-frame.

6. A car comprising a truck including a frame having a bolster mounted thereon, a U-shaped frame mounted upon the bolster, a body disposed slidably in the U-shaped

frame, plates slidably mounted upon the sides of the body, lower wheels mounted in the truck-frame, upper wheels mounted in said sliding plates, bearing-boxes for the axles 5 of the upper wheels in which the axles are engaged, bolsters upon which the boxes are mounted, sustaining-springs for said bolsters mounted upon the truck-frame, and means for adjusting the tensions of the sustaining-
10 springs simultaneously.

7. A car comprising a truck including a frame and supporting-wheels, a U-shaped frame carried by the truck-frame, a car-body mounted in the U-shaped frame, plates slidably mounted upon the sides of the body, additional plates slidably mounted for limited movement in the first-named sliding plates, axles passed through the second-named plates and having wheels lying above and in parallel planes with the corresponding first-named wheels, sills having bearings in which said axles are received, bolts mounted upon the truck-frame and engaged with the bolsters, pinions screwed upon the bolts, springs be-

tween the pinions and the bolsters, and shafts 25 having worm-gears engaged with the pinions and having means for rotating them simultaneously to move the pinions and adjust the tensions of the springs.

8. The combination with a trackway comprising upwardly-converging posts arranged in pairs and having transverse connections, lower rails supported upon the transverse connections and upper rails supported at the upper ends of the posts, of a car having supporting-wheels mounted upon the lower rails and having additional wheels at its sides disposed against the under faces of the upper rails, adjustable tension devices for holding the last-named wheels against the upper rails, 35 and means for adjusting the tension devices.

In testimony whereof I affix my signature in presence of two witnesses.
